ALBERT H. STEBBINS, OF LOS ANGELES, CALIFORNIA.

AIR CLASSIFIER.

Application filed September 24, 1926. Serial No. 137,484.

This invention relates to an air classifier and also to a series of similar classifiers arranged one above the other in stacked relation to subject the materials to successive treatments.

It is frequently desirable in the treatment of ores and other materials to effect the separation of very fine dust-like particles from slightly larger dust-like particles, 10 but such minute particles are hard to classify due to their tendency to remain suspended in the air employed in effecting their classification, and also to the tendency of the smallest particles to cling to the larger particles.

When air is employed to effect a classification of these fine dust-like particles, a complete classification of the particles cannot be effected by a single air treatment, but 20 it is necessary to subject the materials repeatedly to the action of slight air currents which will gently remove the finest particles from the slightly larger particles.

The present invention therefore contemplates 25 a multiple treatment classifier that consists of a number of similar classifying receptacles that are connected in series so that the heavier particles pass from one receptacle to another while some of the finer particles are removed from the larger particles in each receptacle.

One important feature of the present invention resides in the arrangement of the classifying receptacles one above the other 30 in a compact series so that the heavier particles flow by gravity from one receptacle to the other.

Another feature of the invention resides in the construction whereby a fresh supply 35 of air is introduced into each receptacle to pick out the finer particles, and in the construction whereby a single suction conduit serves to remove the air and particles suspended therein from each of the receptacles.

Another feature of the invention resides 45 in the construction of the individual classifying receptacles whereby the heavier particles in approaching the discharge opening are caused to move across a jet of air that 50 serves to pick out the finer particles and carry them upwardly in the receptacle.

Still another feature of the invention resides in the construction whereby the materials to be treated are delivered to the receptacle through a central feed pipe and 55 the air is exhausted from the receptacle

around the feed pipe so that rising air currents are produced entirely around the materials discharge by the feed pipe.

Other features of the invention and novel 60 combination of parts in addition to the above will be hereinafter described in connection with the accompanying drawings which illustrate good practical forms of the invention.

65

In the drawings—

Fig. 1 is a side elevation of a multiple treatment classifier constructed in accordance with the present invention;

Fig. 2 on an enlarged scale is a sectional 70 view taken on the line 2—2 of Fig. 1;

Fig. 3 on an enlarged scale is a vertical sectional view through two of the air classifiers of Fig. 1;

Fig. 4 is a plan view of a spreader-supporting element to be described;

Fig. 5 is a bottom view of the spreader; and

Fig. 6 is a vertical sectional view of a modified construction for admitting air into 80 the lower portion of a classifying receptacle.

The multiple treatment classifier is shown in Fig. 1 as formed of a number of individual classifying receptacles 10 which are disposed one above the other in stacked relation so that the heavier particles being treated will flow, under the influence of 85 gravity, from one receptacle to the next for further treatment.

Each of the receptacles 10 is shown as 90 having an enlarged central portion 11 to which is secured an upwardly extending conical portion 12 and a downwardly extending conical portion 13. The upper conical portion 12 of each receptacle is provided with 95 an opening 14 through which air is exhausted from the receptacle and the downwardly extending conical portion 13 of each receptacle is provided with an opening 15 through which the heavier materials are discharged.

An important feature of the present invention resides in the construction whereby the materials that move downwardly in a receptacle towards the discharge opening 15 105 are directed against a jet or annular blade of air entering the lower portion of the receptacle, and which serves to remove the lighter particles from the heavier particles and to carry these lighter particles up- 110 wardly within the receptacle.

In the construction shown the rising air

currents at the lower end of a receptacle 10 are produced by forming the annular air passage 16 about the lower end of the conical portion 13. At the upper end of each receptacle 10 is provided a casing 17 which is constructed to exhaust air from the upper end of its receptacle, as will be hereinafter more fully described, and the configuration of this casing 10 is preferably such that the inner 10 conical wall 18 of the casing lies in spaced relation to the lower end of the conical portion 13 of the next upper receptacle of the stack, to form the annular air passage 16, as will be apparent from Fig. 3. The adjacent receptacles 10 may be supported in spaced relation one above the other by the braces 19 or by any other suitable supporting structure, and the lower end portion 13 of each receptacle is supported centrally 20 within the upper portion of a casing 17 by the spacing elements 20 shown in Fig. 2.

Each annular casing 17 is provided with a feed pipe 21 which extends downwardly some distance into the interior of a receptacle 10 to deliver the materials to be treated into the same from the next upper receptacle, and the diameter of this feed pipe 21 is such that the annular air passage 14 is formed between this pipe and the opening 30 in the upper end of the conical portion 12 of each receptacle. Each annular casing 17 is connected to the exhaust conduit 22 by a pipe 23 extending from its casing 17 to the exhaust conduit. The conduit 22 preferably 35 increases in diameter in an upward direction to accommodate the increased volume of air passing through the upper portion of the conduit and the upper end of the conduit 22 may be connected to an exhaust fan 24, the 40 blast discharge outlet of which fan is connected to a dust extractor 25 by the pipe 25a. The construction of the annular casing 17 and associated parts just described is such 45 that air is drawn upwardly within each receptacle 10 around the feed pipe 21 and through the annular opening 14 at the upper end of each receptacle, as indicated by the arrows.

As a result of this construction rising air 50 currents are produced entirely around the feed pipe 21. The suction produced in each receptacle 10 by the means just described serves to draw air from the atmosphere inwardly through the annular opening 16 at the lower end of each receptacle, and the heavier materials which pass downwardly 55 within a receptacle in opposition to the rising air currents will settle upon the inclined walls 13 of the receptacle and as they slide down these inclined walls they will be directed against the blade of air entering the 60 passage 16. This will serve to disengage from the larger particles the fine particles which tend to cling to such larger particles 65 and will serve to carry upwardly within the

receptacle the finer particles, while the larger particles may pass through this blade of air into the discharge pipe 21, whereupon such particles will enter the next lower receptacle for further treatment.

It is desirable to provide each receptacle 10 with a spreader which will serve to spread the materials delivered by a feed pipe 21 outwardly towards the side walls of the receptacle. Various means might be provided to 70 this end, and in the construction shown consists of a cone-shaped hollow casing 26 which may be suspended within the receptacle by a rod 27 the upper end of which is connected to a three-way spider 28 mounted within the 75 feed pipe 21. The construction of the spreader 26 is such that materials falling upon the same will be directed outwardly within the receptacle by the inclined walls of the spreader. It may be desirable to provide 80 air currents flowing upwardly around the lower end of the spreader 26. These air currents will serve to disseminate the particles that tend to cling together, and such air currents may conveniently be produced 85 by mounting a disk 29 within the lower end of the spreader 26 so that an annular air passage 30 is provided between the inner wall of the spreader and the edge of such disk. One or more pipes 31 which serve to 90 conduct air from the atmosphere to the interior of the spreader may be provided, and as a result the suction produced within a receptacle 10 will draw air from the atmosphere through the pipes 31 into the spreader 95 26 and this air will escape through the annular slot 30 to produce the desired air currents around the base of the spreader.

In some cases it may be desirable to introduce air at the lower end of a receptacle 105 through two or more annular passages, as shown in the modification of Fig. 6; this construction may be desirable since several jets or blades of air will separate the fine particles from the larger particles more effectively than would a single blade. The modified construction shown in Fig. 6 differs from that shown in Fig. 3 only in that the distance between the lower end of the conical wall 13 of the receptacle and the adjacent conical wall 18 of the air exhaust casing is increased, and in the space thus formed are supported one or more conical shaped rings 32 which serve to form the several air passages 33.

From the foregoing description when read in connection with the drawings, it will be seen that any desired number of classifying receptacles 10 may be supported one above the other in stacked relation so that the heavier materials pass successively through the different receptacles, and that these heavier particles are subjected in each receptacle to rising air currents which will remove some of the lighter particles from the 120 125 130

heavier particles and carry these lighter particles up through the upper end of the receptacle and into the suction conduit 22. The heaviest particles which pass through the entire series of receptacles 10 are discharged into a closed bin 34 and such particles as may settle within the suction conduit 22 will pass downwardly into the closed bin 35. The materials to be treated may be delivered to the uppermost receptacle 10 by a pipe 36 or any other suitable type of feed.

The amount of air required to operate a large number of receptacles 10 will not be excessive because the individual receptacles need not be large, and the strength of air employed in each receptacle will be relatively weak, due to the necessity of employing extremely gentle forces in effecting the classification of fine dust-like particles. By supporting the receptacle 10 in stacked relation as shown, and by connecting each receptacle with the exhaust conduit 22, any desired number of individual receptacles may be operated from a single exhaust pipe, and may be supplied with materials from a single feed pipe. Furthermore, by subjecting the larger particles time and time again to the action of slight rising air currents, the finest particles are gradually removed from the slightly larger particles.

What is claimed is:—

1. An air classifier, comprising in combination, a receptacle having an air inlet opening adjacent its lower end, means for delivering the materials to be treated into the upper part of the receptacle, a hollow spreader supported within the casing below the feed means and having sloping side walls to deflect outwardly the falling particles, means for exhausting air from the upper portion of the receptacle, and a pipe leading from the exterior of the receptacle into the interior of the spreader and adapted to produce air currents around the lower edge of the spreader to diffuse the particles.

2. An air classifier, comprising in combination, a receptacle having an air inlet opening adjacent its lower end, means for delivering the materials to be treated into the upper part of the receptacle, means for exhausting air from the upper portion of the receptacle, a hollow spreader supported within the casing below the feed means and having sloping side walls to deflect outwardly the falling particles, a pipe leading from the exterior of the receptacle into the interior of the spreader and through which air is drawn by said exhaust means to produce air currents around the lower end of the spreader to diffuse the particles.

3. A multiple treatment classifier, comprising in combination, a series of classifying receptacles arranged one above the other in compact relation and each having a feed pipe that extends from its lower end into

the next receptacle to direct the heavier particles from one receptacle into the next, means for admitting air into the lower portion of each receptacle, means constructed to form a narrow annular discharge passage 70 at the upper end of each receptacle about the feed pipe that projects into the same, and a suction pipe leading from the upper portion of each receptacle to exhaust air therefrom through said annular passage. 75

4. A multiple treatment classifier, comprising in combination, a series of classifying receptacles arranged one above the other in compact relation and each having a feed pipe that extends from its lower end into 80 the next receptacle to direct the heavier particles from one receptacle into the next, means for admitting air into the lower portion of each receptacle, an annular casing formed at the upper end of each receptacle 85 about the feed pipe for that receptacle and constructed to provide a narrow annular air passage about the pipe and through which air is exhausted from the receptacle, and a suction pipe for exhausting air from each 90 of said casings.

5. A multiple treatment classifier, comprising in combination, a series of classifying receptacles arranged one above the other in stacked relation and each having a feed 95 pipe that extends from its lower end into the next receptacle to direct the heavier particles from one receptacle into the next, means for admitting air into the lower portion of each receptacle, an exhaust casing 100 provided at the upper end of each receptacle for exhausting air from the receptacle about the feed pipe projecting into the same, an exhaust conduit disposed along side the stack of receptacles, and a connection between 105 each casing and said conduit.

6. An air classifier, comprising, in combination, a receptacle having an enlarged body portion and a protruding conical upper end in which a central opening is formed, 110 a material feed pipe extending through said opening into the receptacle, an annular casing connected to the upper end of the receptacle and surrounding said pipe, means for introducing air into the lower portion of 115 the receptacle, means positioned at one side of said casing for exhausting air therefrom, and said upper converging end of the receptacle being constructed to extend inwardly into close proximity to the outer walls 120 of the feed pipe to form a restricted throat about said pipe that leads from the receptacle to the casing and which is given a size to equalize the strength of the air entering the casing at different points around the 125 feed pipe.

7. An air classifier, comprising in combination, a receptacle having an enlarged central portion and reduced converging end portions, a feed pipe extending into the up- 130

per end of the receptacle, means for introducing air into the lower portion of the receptacle to pass upwardly through the falling materials, an annular air exhaust 5 casing provided at the upper end of the receptacle about the feed pipe and connected to the receptacle by a reduced neck that forms a restricted passage between the receptacle and casing, and means for exhausting 10 air from the casing to draw air upwardly through the receptacle.

8. A multiple treatment classifier, comprising in combination, a stack formed of a large number of small classifying receptacles each having a bulged central portion and oppositely extending converging end portions, means for supporting the receptacles in stacked relation with the lower end of one receptacle extending into the upper 15 end of the next and arranged to admit air from the atmosphere into the lower end of each receptacle, an air exhaust casing at the upper end of each receptacle, a conduit extending lengthwise of said stack, and 20 means for exhausting air from each casing to draw air upwardly through the receptacles and including branch pipes leading from the casings to said conduit.

9. A multiple treatment classifier, comprising in combination, a stack formed of 25

a large number of small classifying receptacles each formed with reduced end portions and a bulged central portion, means for supporting the receptacles in stacked relation so that the heavier particles will 30 flow by gravity from one receptacle to the next, means for introducing air into the lower portion of each receptacle, an air exhaust casing provided at the upper end of each receptacle and connected thereto by a reduced neck, and means for exhausting air 35 from each of said casings to draw air upwardly through the receptacles.

10. A multiple treatment classifier, comprising in combination, a stack of classifying 40 receptacles each formed with reduced end portions and a bulged central portion, means for supporting the receptacles in stacked relation so that the heavier particles will flow by gravity from one receptacle to 45 the next, means for introducing air into the lower portion of each receptacle, an air exhaust casing provided at the upper end of each receptacle and connected thereto by a neck, and means for exhausting air from 50 each of the casings to draw air upwardly through the receptacles.

In testimony whereof, I have signed my name to this specification.

ALBERT H. STEBBINS.
